UNITED STATES PATENT OFFICE.

PETER S. H. NEWELL, OF LEONIA, NEW JERSEY, ASSIGNOR TO THE DIAMOND TOY CORPORATION, OF WILMINGTON, DELAWARE, A CORPORATION OF DELAWARE.

DESIGN FOR A FIGURE TOY.

57,924.

Specification for Design.

Patented May 17, 1921.

Application filed October 14, 1920. Serial No. 417,054. Term of patent 14 years.

To all whom it may concern:

Be it known that I, PETER S. H. NEWELL, a citizen of the United States, residing at Leonia, in the county of Bergen and State of New Jersey, have invented a new, original, and ornamental Design for a Figure Toy, of which the following is a specification, reference being had to the accompanying drawing, forming part thereof.

In the drawing—

Fig. 2 is a plan of a figure toy showing my new design.

I claim—

The ornamental design for a figure toy, substantially as shown.

PETER S. H. NEWELL.
